UNITED STATES PATENT OFFICE.

WILLIAM L. MCGRATH, OF ELMIRA, NEW YORK, ASSIGNOR TO ECLIPSE MACHINE COMPANY, A CORPORATION OF NEW YORK.

ENGINE STARTER.

Application filed February 3, 1923, Serial No. 616,668. Renewed March 21, 1927.

My invention relates to means for starting an engine such as an internal combustion engine and has relation more particularly to the drive or transmission between the prime mover such as an electric motor and the part or member of the engine to be started, such as the flywheel thereof. The object of my invention is to provide a simple and efficient drive or transmission which is associated with a vertically disposed electric motor and which is constructed and arranged for manual operation to permit the engagement of a driving member, forming a part of such drive, with the engine member, and for automatic disengagement of such driving member from the engine member or flywheel. By my construction of drive I obtain new operations and results which will be apparent from the description hereinafter given.

20 In the drawings, Figure 1 is an elevation partly in section of an engine starter system embodying my invention; Fig. 2 an end view of the driving member or pinion; Fig. 3 a sectional elevation of the drive or transmission but on a larger scale than in Fig. 1; and Figs. 4 and 5 sectional elevations of such drive illustrating different positions of the movable parts and on a smaller scale than in Fig. 3.

30 For the sake of a clear and definite description of my invention, I have shown the same embodied in one particular construction, but it will be understood that the embodiment thereof may partake of different forms and constructions without departing from the spirit and scope of my invention. Moreover, the drive may be of the indirect type instead of direct as herein shown, and furthermore, in such indirect type, the axis of the starting motor need not be parallel to the axis of the drive proper.

45 Referring to the embodiment of my invention as herein shown, the electric motor 1 is vertically disposed, that is, its armature shaft is in a vertical position. As shown and by preference the motor is supported by the internal combustion engine 2 by being secured thereto by the bolts 3. The armature shaft 4 of the motor is extended beyond the frame 50 of such motor and its lower end is journaled in a bearing 5 in a casing 6 which is secured to and depends from the motor frame.

55 The drive or transmission is made as an assembly which is readily applicable to and removable from the armature shaft. This

drive comprises a screw shaft or sleeve 7 mounted loosely upon the armature shaft. This sleeve has an intermediate screw-threaded portion 8 and on its upper smooth portion there slides a shifter sleeve 9 having a circumferential groove 10 which cooperates with the shifter mechanism hereinafter described. The screw shaft or sleeve is provided at its lower end with suitable stop means such as the stop nut 11. The driving member which is here in the form of a pinion 12 is threaded upon the screw threads 8. The teeth of the pinion are inclined or beveled and adapted to engage the correspondingly inclined or beveled teeth 13 of the engine member which is here the flywheel 14. The screw threads 8 have a long lead for a purpose hereinafter made apparent during the description of operation.

60 Means are provided for holding the pinion in a raised or disengaged position as shown in Fig. 3. Such means here comprise a latch 15 pivoted at 16 in a longitudinal groove in the shifter sleeve and spring-pressed inwardly as to its upper end by a plunger 17 and spring 18. The shifter sleeve has a pin and slot connection with the screw shaft as shown at 19 and 20 in order to have an independent longitudinal movement with respect to such screw shaft. The body of the latch works in 75 a slot 21 in such screw shaft. This pinion is provided at its upper end with a recess or notch 22 as shown in Fig. 2 in order to engage the lower end of such latch. It will be understood that the latch 15 has a fixed angular 80 relationship with the threads of the screw shaft and since the pinion is screw threaded on the shaft and since the notch 22 is purposely located with relation to the thread openings in the pinion, the end of such latch, 85 on the demeshing movement of the pinion, will enter a thread opening (such as seen at the the right of notch 22 in Fig. 2) and, riding on the inclined surface of the thread, the same will be depressed against the pressure 90 of its spring 18, until the rotation of the pinion as imparted to it by the flywheel brings the notch 22 into register with the latch, whereupon the latch will snap into the notch. 95

100 The screw shaft is operatively connected with the motor by means of the driving head 23 which is secured thereto by the bolt 24 and by the drive spring 25 connected at its opposite ends to such driving head 23 and to the driven head 26 here forming a part of 110

the screw shaft. The drive spring is connected to such driven head 26 by means of the bolt 27.

Next describing the shifter connections, of 5 which a recommended form is shown in Fig. 1, the same comprises a lever or plunger 28 which is here shown as a foot lever working through the foot board 29 of an automobile for instance and pivoted at 30 to the under- 10 side thereof. This foot lever is of irregular shape and is provided with a heel 31 engaging a normally upwardly spring-pressed vertical plunger 32 which has bearings in the brackets 33 projecting laterally from the 15 motor frame and the casing 6. This plunger is normally upwardly spring-pressed by means of a spring 34 bearing at its lower end against the upper bracket 33 and at its upper end against a head 35 secured to the upper 20 end of such plunger 32. This head 35 is provided with a laterally projecting portion or finger in whose path is interposed a movable button 36 of the motor switch 37. Towards its lower end, the plunger 32 is provided with 25 a pivoted latch 38 in whose path of movement is interposed a lever 39 pivoted at 40 in a lateral opening in the casing 6. The inner end of this lever 39 projects into the casing 6 and is formed as a round head 41 which en- 30 gages the groove 10 of the shifter sleeve. This lever 39 is held in a normal position by means of a coil spring 42.

Describing a cycle of operation and start- 35 ing with the normal position of the parts as illustrated in Figs. 1 and 3, when the foot lever 28 is operated and the plunger 32 there- 40 by depressed, the shifter sleeve 9 will be raised and the latch will be removed from the notch 22 of the pinion with the result that the pinion will be permitted to move down- 45 wardly spirally by gravity to the position shown in Fig. 4, at which time the switch button 36 is operated and the motor is started whereupon the rotation of the screw shaft will cause the automatic engagement between 50 the pinion and the flywheel. During this pe- 55 riod of engagement the motor attains a con- siderable speed of rotation so that when the pinion contacts the stop 11, there exists, due to the inertia of the flywheel and engine parts 60 thus suddenly connected to the rapidly re- volving armature, a sudden slowing down of the rotating armature accompanied by a torque caused by this deceleration which, due 65 to its sudden application, would be destruc- 70 tive in its effects were it not for the spring 25 which is interposed in the line of transmission of torque and provides through its yielding a time interval so that this deceleration torque is properly limited in its extent and 75 utilized efficiently in the "breakaway" or ini- tial overcoming of the inertia of the flywheel and associated parts. The parts are now in 80 cranking position as shown in Fig. 5 and the 85 engine will thereupon be cranked. When the 90

engine starts on its own power, the pinion will be automatically demeshed by being screwed backwardly, that is, upwardly upon the screw shaft until it comes within the range of action of the latch 15 whereupon such latch will 70 engage the notch 22 as shown in Fig. 3, such shifter and its latch having by that time been restored to normal position as shown in Figs. 3 and 5. The pinion is thereby held against any return to lowered position against the flywheel, and this is true whether the operator or driver has released pressure upon the foot lever 28 or not inasmuch as the depression of such lever 28 and plunger 32 such as illustrated in Fig. 5 does not prevent the re- 75 turn of the shifter sleeve to normal position because of the use of the pivoted latch 38 which permits of the return of the shifter sleeve to normal position before such plunger 32 reaches its lowermost limit of movement. In other words, such latch 38 passes by the lever 39 after the latter has performed its shifting function and such latch wipes by 80 such lever on its upward stroke by tilting the latter. 90

I claim:

1. An engine starter including a vertically disposed rotatable shaft, a drive mounted thereon and driven thereby and including a sleeve, a driving member mounted on the sleeve for rotary movement therewith and for longitudinal movement thereof and movable by gravity to engage a member of the engine to be started, and manually controlled means for holding the driving member in retracted position. 95

2. An engine starter including a vertically disposed rotatable shaft, a drive mounted thereon and driven thereby and including a screw threaded sleeve, a driving member threaded on the sleeve and movable by gravity to engage a member of the engine to be started, and manually controlled means for holding the driving member in retracted position. 105

3. An engine starter including a vertically disposed rotatable shaft, a drive mounted thereon and driven thereby and including a screw threaded sleeve, a driving member threaded on the sleeve and movable by gravity to engage a member of the engine to be started, a manually controlled latch for holding the driving member in retracted position. 115

4. An engine starter including a vertically disposed rotatable shaft, a drive mounted thereon and driven thereby and including a screw threaded sleeve, a driving member threaded on the sleeve and adapted to engage a member of the engine to be started, the threads on the sleeve having a long lead whereby the driving member will, when released, automatically move by gravity on such threads, and means for holding the driving member in a normally retracted position. 120

130

5. An engine starter including a vertically disposed rotatable shaft, a drive mounted thereon and driven thereby and including a screw threaded sleeve, a driving member 5 threaded on the sleeve and adapted to engage a member of the engine to be started, the threads on the sleeve having a long lead whereby the driving member will, when released, automatically move by gravity on 10 such threads into contact with the engine member, means for automatically establishing the driving connection between the driving member and the engine member, and means for holding the driving member in a 15 normally retracted position.
6. An engine starter including a vertically disposed rotatable shaft, a drive mounted thereon and driven thereby and including a screw threaded sleeve, a driving member 20 threaded on the sleeve and adapted to engage a member of the engine to be started, the threads on the sleeve having a long lead whereby the driving member will, when released, automatically move by gravity on 25 such threads, into contact with the engine member, means including a yielding driving connection for automatically establishing the driving connection between the driving member and the engine member, and means 30 for holding the driving member in a normally retracted position.
7. An engine starter including a vertically disposed rotatable shaft, a drive mounted thereon and driven thereby and including a screw threaded sleeve and a pinion threaded 35 on the sleeve and adapted to engage a member of the engine to be started, the threads on the sleeve having a long lead whereby the pinion will automatically move by gravity on such threads, means for holding the pinion 40 in a raised position after disengagement from the engine member, and a manually operated device for controlling said means.
8. An engine starter including a vertically 45 disposed rotatable shaft, a drive mounted thereon and driven thereby and including a screw threaded sleeve and a pinion threaded on the sleeve and adapted to engage a member of the engine to be started, the threads 50 on the sleeve having a long lead whereby the driving member will automatically move by gravity on such threads, a shifter sleeve mounted to slide on the screw sleeve, a catch 55 device mounted on the shifter sleeve and adapted to hold the pinion in raised position 60 on the sleeve after disengagement from the engine member, and means for operating the shifter sleeve.
9. An engine starter including a vertically disposed rotatable shaft, a drive including a screw sleeve mounted on the shaft, a yielding driving connection between it and the shaft, a pinion threaded on the sleeve for longitudinal movement thereof and rotary movement therewith, said pinion being movable 65 by gravity to engage a member of the engine to be started, means for holding the pinion in a normally retracted position, and a manually operated device for controlling said means.
10. An engine starter system including an electric motor with a vertically disposed extended armature shaft, a bracket depending from the motor and having at its lower 70 end a bearing for the lower end of such shaft, a drive assembly including a screw sleeve mounted on the shaft and driven thereby, a pinion threaded on the sleeve for longitudinal movement thereof and rotary movement therewith, said pinion being movable by 75 gravity to engage a member of the engine to be started, means for holding the pinion in a normally retracted position, and a manually operated device for controlling said means.
11. An engine starter including a vertically 80 disposed rotatable driving shaft, a drive mounted thereon including a sleeve drivingly connected with the shaft and a driving member drivingly operable thereby and mounted thereon for longitudinal movement and normally out of engagement with a member of the engine to be started but movable by gravity to engage such engine member.
12. An engine starter including a vertically 85 disposed rotatable driving shaft, a drive mounted thereon including a sleeve drivingly connected with the shaft and a driving member drivingly operable thereby and mounted thereon for longitudinal movement and normally out of engagement with a member of the engine to be started but movable by gravity to engage such engine member and means for holding the driving member in its normal or retracted position.

WILLIAM L. McGRATH.
